UNITED STATES PATENT OFFICE.

FREEBORN F. RAYMOND, 2d, OF NEWTON, MASSACHUSETTS.

NAIL DISTRIBUTING AND FEEDING MACHINE.

SPECIFICATION forming part of Letters Patent No. 379,330, dated March 13, 1888.

Application filed October 27, 1887. Serial No. 253,485. (No model.)

To all whom it may concern:

Be it known that I, FREEBORN F. RAYMOND, 2d, of Newton, in the county of Middlesex and State of Massachusetts, a citizen of the United States, have invented a new and useful Improvement in Nail Distributing and Feeding Machines, of which the following is a full, clear, and exact description, reference being had to the accompanying drawings, forming a part of this specification, in explaining its nature.

The object of the invention is to provide a simple and efficient means for distributing and feeding nails in gangs or groups to a nail carrier or templet, or to nail-conducting passages.

The invention is represented as embodied in a machine containing nail-making devices similar to those described in the application of Chester C. Small, filed April 21, 1887, Serial No. 235,648, and no description of the nail-making devices is herein necessary, it being sufficient to state that the nails are made and delivered in successive order through a throat.

In the drawings, Figure 1 is a view in side elevation of a machine having the features of my invention. Fig. 2 is a view in rear elevation thereof. Fig. 3 is a central vertical section. Fig. 4 is a view in horizontal section upon the line $x-x$ of Fig. 3 and in plan of the parts below said line. Figs. 5, 6, and 7 are detail views.

A is the throat of the machine. This throat is formed in a nozzle or block, a , and there is arranged below it a nail-receiving block, B , which has a number of nail-receiving holes, b , therein, arranged in a circular order. The nail-receiving block has holes for the largest number of nails which it may be desirable to distribute and drive at any one time. It is mounted upon the shaft b' and has a hole-covering plate, b^2 , which rotates with it and which has perforations or holes b^3 , adapted to be brought into line with the holes b when it is desirable to discharge them or permit the nails which they carry to escape from them. This plate is moved to cover and uncover the holes, as hereinafter described. There is formed upon the periphery of the block B a ratchet-wheel, C , by which the block is rotated in con-

nection with the feed-pawl c with an interrupted or intermittent movement in one direction. This feed-pawl c is carried by a slide-block, c' , and is operated by a cam, c^2 , upon the shaft c^3 of the nail-making machine and the lever c^4 . The block also has the ratchet-wheel D , the teeth of which number the same as the teeth of the ratchet C , but are oppositely inclined. This ratchet operates in conjunction with the pawl d and the feed-pawl c to accurately lock the block at the end of the feed movement of the pawl c , so that each hole b shall register with the throat A . This locking-pawl d is operated by means of the cam d' on the shaft c^3 of the nail-making machine and the lever d^4 .

The operation of this part of the machine is as follows: The cams d' c^2 are timed so that the stop-pawl d is moved into a position slightly in advance of the end of the feed movement of the feed-pawl c , to act as a stop or abutment against which a tooth of the ratchet D shall come in contact, and the feed-pawl c , by contact with a tooth of the ratchet-wheel C , continues to move the block forward until a tooth of the ratchet D comes in contact with the end of the pawl d . This causes the block to be locked between the two pawls, and after the hole which is in register with the throat has received its nail the cam c^2 acts to withdraw the pawl c to permit it to engage the next tooth of the ratchet-wheel C in order, and the cam d' then acts to withdraw the pawl d and holds it until the tooth which it engaged has passed beyond it sufficiently to clear its point, when it is again moved forward to act as a stop.

The object of the block B is to permit any desired number of nails to be made upon a forward movement of the block in one direction and to be delivered upon the rotation of the block in the opposite direction, and in order to permit this reverse rotation to take place it is of course necessary to disengage the feed-pawl c from the ratchet-wheel C .

To return the block B to its original position, or, in other words, to provide it with a reverse movement of rotation, there is attached to it the drum b^4 , (see Fig. 1,) to which the end of a draw cord or rope, b^5 , is attached. This draw-

cord extends over a pulley, b^6 , and carries a weight, b^7 . To hold the block B when it is moved forward by the ratchet c against the pull of the weight b^7 , I use a detent, E, which 5 engages the teeth of the ratchet-wheel C and serves to hold the block B while the feed-pawl c is being moved backward to engage the next ratchet-tooth in order.

To enable the weight to rotate the block B backward to its original position, it is necessary to release this pawl E and hold it disengaged. This is accomplished by means of a tripping-block, F, which is mounted upon the block B to be rotated therewith, it having two 15 pins, f , which enter the holes b , and the extension f' , that extends beyond the line of the face of the teeth of the ratchet-wheel C, and upon the rotation of the block B this tripping-block comes in contact with the detent-pawl E and 20 moves it from engagement with the ratchet-teeth sufficiently to permit the spring-latch f^3 to engage it and hold it disengaged from the ratchet-teeth C, and the detent-pawl occupies this position until it is released at the end of 25 the return movement of the block B, when the latch f^3 is disengaged from the detent E by means of the lifting-lug f^4 on the block B, which, riding under the end of the spring-latch f^3 , lifts it sufficiently to allow the spring of the 30 detent E to move it to its normal position.

To operate the hole-covering plate b^8 , I have provided the plate with an arm, g , which is adapted to come in contact with the stop g' at the end of the backward movement of the 35 block B. This causes the plate to be turned sufficiently to bring its holes in register with the holes b . Upon the forward movement of the block B the spring g^2 turns the plate immediately upon the starting of the block sufficiently to close the holes. 40

I have represented as used in connection with the block B a distributor, H, which comprises the block h , made upon the arc of a circle, having holes h' , which are arranged upon 45 the same line and order of the holes b of the nail-holder B. The holes h' are connected by passages h^2 in the tubes h^3 with a stationary nail-holder, h^4 , or directly with a nail-carrier or a templet.

50 It will be observed that by means of this block B any desired number of nails may be received for delivery from one to the largest number of holes in the block; also, that the block is always returned to its original position to deliver its nails, being automatically stripped or disengaged from its feeding mechanism upon the making and delivery to it of that number, and is then automatically returned to its original position, and the nails as 55 received are automatically delivered to the passages of the distributing-tubes.

The mechanism for starting and stopping the nail making or supplying devices is similar to those described in said Small application. 65

Having thus fully described my invention,

I claim and desire to secure by Letters Patent of the United States—

1. The combination of a nozzle or block having a throat, through which nails are delivered in consecutive order, with a block, B, having nail-receiving holes b arranged in circular order therein at a uniform distance apart, a feeding device providing the block with periods of rotation and rest in one direction, and 70 a weight or other equivalent actuating device connected with the block and adapted to rotate the block in a reverse direction, substantially as described. 75

2. The combination of a block or nozzle having a throat, A, through which nails are delivered in successive order, the block B, having the circular line of holes b and a hole-covering plate, b^2 , the ratchet-wheel C, the reciprocating pawl c , the drum b^4 , the cord b^5 , 80 weight b^7 , substantially as described. 85

3. The combination of a block or nozzle having a throat, A, through which nails are delivered in successive order, the block B, having the circular line of holes b and a hole-covering plate, b^2 , the ratchet-wheel C, the reciprocating pawl c , the drum b^4 , cord b^5 , weight b^7 , and detent E, substantially as described. 90

4. In a nail distributing and feeding machine, the block B, having the holes b and 95 covering-plate b^2 , adapted to be rotated with an intermittent movement in one direction and continuously in a reverse direction, its ratchet-wheel C, the detent-pawl E, and a tripping-block for releasing the detent-pawl, and a latch 100 for engaging and holding the detent-pawl during the backward movement of rotation of the block, substantially as described.

5. The combination of the block B, the detent-pawl E, the tripping-block F, and the detent-latch f^3 , substantially as described. 105

6. The combination of the block B, the detent E, its latch f^3 , and latch-lifting lug f^4 , substantially as described.

7. The combination of the rotary block B, 110 having the holes b and hole-covering plate b^2 , having perforations b^3 , arm g , stop g' , and spring g^2 , substantially as described.

8. The combination of the rotary block B, having the holes b , the ratchet-wheels CD, the 115 registering-pawl d , and the feed-pawl c , as and for the purposes described.

9. The combination of the block or nozzle having the throat A, through which nails or fastenings are delivered in successive order, 120 the rotary nail-receiving block B, having the holes b and hole-covering plate b^2 , the intermittently-operated feeding device for rotating the block in one direction, devices for returning the block to its original position upon the 125 making of a given number of nails, and the nail-distributer H, substantially as described.

10. In a nail-distributing machine, a nail receiving and carrying block having a number of nail receiving and holding holes arranged in a circular or curved line therein and 130 adapted to be rotated intermittently in one

direction to receive nails and to be rotated in a reverse direction to deliver the nails, substantially as described.

11. The combination of a rotary block having a circular line of holes, a reciprocating pawl for communicating an intermittent rotation to the block in one direction, devices for automatically rotating the block in a reverse

direction, and a movable tripping-block for governing the time of operation of the devices for providing the reverse rotation, substantially as described.
